WEB SPLICING DEVICE FOR NEWSPAPER PRESSES

Eugene P. Doyle and Leo F. Long, Toledo, Ohio

Application October 4, 1937, Serial No. 167,100

7 Claims. (Cl. 242—58)

This invention relates to web splicing or pasting devices for newspaper presses in which a web from a fresh roll of paper is applied or adhesively connected to the web from a nearly exhausted roll of paper and an object is to produce a new and improved method and apparatus for splicing such paper webs together during the operation of the press at full press speed in such manner that an efficient and satisfactory paster is effected without loss of time and with a minimum of paper waste and in a simple and efficient manner.

Other objects and advantages of the invention will hereinafter appear and for purposes of illustration but not of limitation, an embodiment of the invention is shown on the accompanying drawings in which

Figure 1 is a side elevation partly diagrammatic of a reel for paper rolls showing the mechanism for splicing the web of a new paper roll to the web from a roll which is substantially exhausted, the parts being shown substantially at the time when the web from the exhausted roll is severed;

Figure 2 is a partly diagrammatic view showing a side view of a paper roll and the driving wheel for driving the paper roll at press speed disposed in inoperative position;

Figure 3 is a view somewhat similar to Figure 2 showing the driving wheel in driving contact with the paper roll;

Figure 4 is an enlarged view partly in section and partly diagrammatic showing the web severing mechanism;

Figure 5 is a sectional view substantially on the line 5—5 of Figure 3 with some of the parts omitted for purposes of clarity to illustrate the connection between certain of the parts and the spring cable arrangement which urges the cam disc to its depending position; and

Figure 6 is a wiring diagram showing the electrical circuits controlling the operation of the several parts.

The illustrated embodiment of the invention comprises a standard 10 on which a three-arm reel 11 is rotatably mounted. Suitably carried by the arms of the reel 11 are fresh paper rolls A and B and a roll C, the paper web of which is substantially exhausted. The reel is driven in any suitable manner from an electric motor 12 so that the reel can be rotated in a counterclockwise direction for bringing fresh rolls or successively the rolls B and A into operative position, the roll C being shown in the operative position or the position assumed when the web such as

the web 13 leading from the roll C extends to the newspaper press (not shown).

At the proper time, the oncoming roll or the roll whose web is to replace the web from the exhausted roll is driven by a wheel 14 which has a friction producing rim 15 such as rubber or other suitable material. The wheel 14 is brought into contact with the end of the roll, such as the roll B in the form shown near the peripheral surface thereof about one-eighth inch therefrom. The wheel 14 is driven in any suitable manner from the newspaper press so that the paper roll B is driven thereby at press speed. The wheel 14 is mounted on the outer end of an arm 16 the upper end being pivotally connected to an arm 17, the latter having an extension 18 and interposed between the free end of the extension 18 and the arm 16 is a coil spring 19. On the opposite end of the arm 17 is an upwardly and outwardly inclined portion 20 on the free end of which is disposed a roller 21. The roller 21 engages the outer surface of a cam disk 22. The cam disk 22 is eccentrically mounted about a pivot 23. In diametrically opposed relation to the axis 23 of the cam disk 22 is a pin 24 which is engageable by an arm 25 having a notched outer end.

In the normal position of the parts as shown on Figure 2 in which the driving wheel 14 is disposed in inoperative position, it will be noted that the pin 24 is lowermost and is engaged by the notched arm 25. The notched arm 25 is suitably connected to a shaft 26 having an operating handle 27, the arm 25 may be swung in a clockwise direction (Figure 3), thereby imparting similar movement to the cam disk 22 and raising it to the position shown in Figure 3, whereupon the notched end of a lever 28 engages the pin 24 and holds the cam disk 22 in such position. After the cam disk 22 has been raised and the notched lever 28 has engaged the pin 24, the operator releases the handle 27 which thereupon swings downwardly to its normal position, returning the arm 25 to its normal position as shown in Figure 3. When the cam disk 22 is swung from the position shown in Figure 2 to the position shown in Figure 3, the driving wheel 14 is swung inwardly into engagement with the end of the paper roll B thereby operatively to drive the roll B. The opposite end of the lever 28 is connected to a solenoid generally indicated at 29, a spring 30 normally urging the arm 28 into pin-engaging position. It will be apparent that upon energizing the solenoid 29, the arm 28 is rocked sufficiently to

cause the arm 28 to release the pin 24 and the cam disk 22 is returned to normal position being normally urged to such position by a spring cable 31, the outer end of which is suitably connected to a sheave 32. It should be noted that the above described parts are mounted on a bracket 33 which is suitably suspended from supporting rods 34.

In operation, the free end of the oncoming roll 10 such as the roll B is coated with adhesive and at the proper time the reel 11 is rotated in a counterclockwise direction to bring the pasted end into engagement with the web 13 from the exhausted roll C. During such movement of the reel, the 15 paper roll B is moved into contact with a relatively soft composition roll 35 which is carried by a bracket arm 36. Movable with the bracket arm 36 is a sprocket wheel 37 which is connected by a chain 38 to a smaller sprocket wheel 39 fixed 20 to a sheave 40. Secured at one end to the sheave 40 is a cable 41 to the lower end of which is a relatively small weight 42. The cable extends through an opening in a larger weight 43 which is moved upwardly by the weight 42 when the 25 sheave 40 is rotated in one direction. The larger weight 43 has a sheave 44 at its upper end which is connected by a cable 45 to a sheave 46 having a weight 47. In opposed relation to the sheave 44 is a sheave 48 having a cable 49 which extends 30 upwardly over a sheave 50 and thence downwardly to a sheave 51 to which is fixed a sprocket wheel 52. Over the sprocket wheel is trained a chain 53 the lower portion of which passes around a sprocket wheel 54 and then extends upwardly 35 through a guide housing 55 the upper end thereof being connected to a carriage 56. The portion of the chain 53 which extends downwardly from the sprocket 52 is secured at 51 to the carriage 56. The carriage 56 is movable up and down in the 40 guide housing 55 and is provided with a laterally extending bracket 58 on which is pivotally mounted a bell crank 59 on one end of which is mounted a roller 60 the other arm 61 of which being adapted to extend outwardly from the housing 56 a substantial distance to engage the web 13 and 45 break or sever it from the exhausted roll C. The bell crank 59 is normally urged to the position shown in Figure 4 or to web severing position by a coil spring 62 one end of which is anchored to the bracket 58 and the opposite end of which is connected to the arm 61. Extending outwardly from the bell crank substantially in alignment with the roll carrying arm and secured by movement therewith is a trip arm 63 which is adapted to be engaged by a catch lever 64 which 50 is notched to receive the arm 63. The catch lever 64 is pivotally mounted at 65 on the carriage 56 and is urged outwardly or into arm engaging position by a coil spring 66. The solenoid 67 is associated with the catch lever 64 and is adapted 55 when energized to swing the catch lever 64 to the left of Figure 4 to release the arm 63.

When the carriage 56 is moved upwardly its upward movement is limited by an arm 68 which 60 is connected to the lower end of the carriage 56 and projects outwardly a sufficient distance to engage the underside of the exhausted roll C so that the web severing arm 61 is disposed in the desired position for severing the web 13. The stop 65 arm 68 functions to hold the severing mechanism in the desired position but the severing operation takes place subsequently. When the carriage 56 is moved downwardly the roller 60 on the bell crank 59 engages a stationary cam track 69 which 70 is so designed as to rock the bell crank 59 in a

counterclockwise direction sufficiently so that the arm 63 is moved into latching engagement with the catch lever 64.

A notch 70 is formed in the rear face of the carriage 56 adjacent the lower end thereof and is adapted to receive an arm 71 for retaining the carriage in its lowermost position. The L-shaped arm 71 is controlled by a solenoid 72 which, when energized, swings the L-shaped arm 71 outwardly to release the carriage 56 to allow 10 the same to move upwardly for effecting severance of the web 13.

Rotatable with the roll B is a disk 73 of fibrous or other suitable non-conducting material and carried thereby is an elongate plate 74 of copper 15 or other suitable conducting material. The plate 74 is adapted to engage contact 75 and 76 carried by a stationary post 77 for a purpose which will hereinafter appear.

In operation of the above described mechanism, 20 the reel 11 is first rotated in a counterclockwise direction so that the roll B is at a predetermined distance from the travelling web 13, adhesive having been previously applied to the new roll. About one inch spacing is sufficient. Thereupon, 25 the handle 27 is actuated to bring the driving wheel 14 into operative engagement with the end of the paper roll B. This same operation causes the solenoid 72 to be energized thereby to release the carriage 56 permitting it to move upwardly 30 in the guide housing 55 into operative position relative to the exhausted roll C. As shown on Figure 6, when the handle 27 is moved to bring the driving wheel 14 into operative position, the turning movement of the shaft 26 in which the 35 handle is mounted, closes, through any simple mechanical connection, the switch 85, one terminal of which is connected by a lead 86 to the solenoid 72. Extending from the solenoid 72 is a lead 81 which is connected to one pole of the current source, as indicated. The other terminal of the switch 85 is connected by a lead 88 to the other pole of the current source. It will be understood that when the handle 27 is moved in this manner, the contact member 78 on the extension 18 of the arm 17 is moved away from the contact elements 79.

Thereupon, the paster button or control button 80 is depressed to release the latch lever 28 to enable the driving wheel 14 to move away or swing by gravity away from the paper roll B. As shown on Figure 6, depression of the paster button 80 closes a circuit comprehended by the lead 87 and a lead 89 which joins the solenoid 29 and then connects with the lead 88, thereby energizing the solenoid 29 which actuates the lever 28 to release the cam disc 22 which allows the driving wheel 14 to swing away from the paper roll. After the driving wheel 14 has moved a sufficient distance away, the contact member 78 60 on the extension 18 of the arm 17 engages the contact elements 79 and, through the following described connections, energizes the reel motor 12 causing it to turn in a counterclockwise direction (Figure 1), but before that action can take place, 65 the contact arms 75 and 76 must first have engaged the conducting plate 74 on the rotating disk or paster timer 73, the contact arms being connected through suitable relays to complete the circuit to the motor 12. In this connection, 70 it will be observed in Figure 6 that the first revolution of the paper roll B brings the contact plate 74 into engagement with the contact arms 75 and 76, thereby closing a circuit which includes a lead 90 connected to the lead 89, a lead 91, relay 75

switch 92, lead 93, solenoid coil 94, lead 95, and contacts 79 which have previously been connected by the contact member 78, and finally lead 96. Energizing of the solenoid coil 94 operates to move the armature 97 in such manner as to operatively connect switches 98 and 99. When the switch 98 is closed, current is supplied to the reel motor 12 through leads 100 and 101 and leads 102 and 95.

Upon the second revolution of the new roll or roll B, a contact between the contact arms 75 and 76 and conducting plate 74 operates through suitable relays to energize the solenoid 67 to release bell crank 59 and thereby cause the arm 61 or kicker to break the web 13. For this purpose, it will be understood that, at the same time the solenoid 94 is energized, a solenoid 103 is energized by a circuit including a branch lead 104, which extends to one pole of the current supply as will be apparent, and a branch lead 105, which extends to the other pole of the current supply through leads 102, 95, contacts 79, contact member 78 and lead 96. The solenoid 103 is preferably of the usual delayed action type, so that movement of the switch 92 from its normal position in engagement with the contact 106 into engagement with the contact 107, is delayed. Thus it will be apparent that the switch 92 is brought into engagement with the contact 107 when the contact plate 74 makes its second revolution, so that when the plate 74 engages the contact arms 75 and 76, the second time, current then flows through the lead 90 from the connections described, through the lead 91, switch 92, contact 107, lead 108, solenoid 67, and lead 109 to the lead 98. It will be noted that after the contact plate 74 in its first revolution has passed over the contacts 75 and 76, current is still supplied to the solenoids 94 and 103 through the lead 87, control button or switch 88, lead 90, switch 99, lead 110, solenoid 94, solenoid 103 which is connected in parallel with solenoid 94, lead 95 and thence to the current source as above described through contact plate 78.

Thereafter, the roll B abutting against the soft composition roll 35 swings the latter outwardly and through the connections above described lifts the weights and allows the carriage 56 to lower to such position that it is caught by the L-shaped arm 71 for the next operation. The paster button or switch 80 is then released, whereupon the solenoids 94 and 103 are de-energized, breaking the circuit to the reel motor 12, and the paster operation is thus completed.

It is to be understood that the illustration is diagrammatic but is sufficient to enable those skilled in this art to practice this invention.

It is to be understood that numerous changes in details of construction, arrangement and operation may be effected without departing from the spirit of the invention especially as defined in the appended claims.

What we claim is:

1. In a newspaper press having a web-splicing device provided with a rotatable reel supporting a plurality of paper rolls adapted to be brought into operation successively, a rotating driving wheel actuated by press speed frictionally engaging one of said rolls at an end and adjacent the periphery thereof and having its axis disposed at substantially right angles to the axis of the paper roll.

2. Apparatus in accordance with claim 1 having a mounting for said wheel normally holding same in inoperative position, means for actuating said wheel to operative engagement with the roll, and means for releasing the wheel and allowing it to return to inoperative position.

3. Apparatus in accordance with claim 1 having manual means for moving the wheel to operative position, and electromagnetic means for rendering the wheel inoperative.

4. In a newspaper press having a web-splicing device, a rotating driving wheel actuated at press speed frictionally engaging one of said rolls at an end and adjacent the periphery thereof and having its axis disposed at substantially right angles to the axis of the paper roll, means for moving said driving wheel to inoperative position, means for rotating said reel, and means enabling said roll rotating means to operate only after said wheel has moved to inoperative position.

5. In a newspaper press having a web-splicing device provided with a rotatable reel supporting a plurality of paper rolls adapted to be brought into operation successively, a swingably mounted roller engageable by an oncoming paper roll upon rotation of said reel, a web-severing device operatively associated with said roller for severing the web from a preceding roll upon splicing the web from the oncoming roll thereto, means separate from the swingably mounted roller for rotating said oncoming roll, and means controlled by rotation of said oncoming roll for rendering said severing device operative.

6. In a newspaper press having a web-splicing device provided with a rotatable reel supporting a plurality of paper rolls, a friction driving wheel actuated at press speed and operatively engaging one of said rolls at an end and close to the periphery thereof, manual means for moving said wheel to operative position, electromagnetic means for rendering said wheel inoperative, and reel rotating means operative only after said wheel has been rendered inoperative, said rotating means being rendered operative in response to rotative movement of said driven paper roll.

7. Apparatus in accordance with claim 6 having a web-severing device, and means responsive to rotation of said driven roll for rendering said device operative.
